COVER FOR STRAINING PAINT FROM CANS

Filed Aug. 8, 1947

Fig. 1.

Fig. 3.

Fig. 4.

Fig. 2. INVENTOR.
Vincenzo Galletta
BY Victor J. Evans & Co.

ATTORNEYS

first removing the original closure or lid and then applying the closure of the drawing to facilitate emptying the contents from the can, as well as for use in mixing the contents of two or more cans. As the paint flows from the mouth 5 the flanges 12, 12 guide the flowing paint into the spout 11 without spilling or waste.

Having thus fully described my invention what I claim as new and desire to secure by Letters Patent is:

1. The combination with a paint can having an open center end wall and a depressed annular groove therein, of a cover having an annular bead for frictional engagement in said groove, said cover adapted to fully close the open center end wall of the can and having vent openings and a screened mouth, and an exterior spout surrounding a portion of the screened mouth.

2. The combination with a container having an open-center head and a depressed annular groove 15 therein, of a cover adapted to entirely close the open center head and having a complementary bead seated in the groove, said cover having op-

10 posed diametrically arranged vent and mouth openings, and a radially extending spout surrounding a portion of the mouth and projecting from an edge of the cover.

VINCENZO GALLETTA.
